UNITED STATES PATENT OFFICE.

BLANCHE STEVENS-ARVOY, NÉE RENEAUX, OF PARIS, FRANCE, AND CHARLES LIONEL MARCUS, OF NEW YORK, N. Y.

DESIGN FOR A COMBINED STAND AND HOLDER FOR PERFUME BOTTLES.

Application filed December 12, 1924. Serial No. 11,689. Term of patent 3½ years.

To all whom it may concern:

Be it known that BLANCHE STEVENS-ARVOY, née RENEAUX, citizen of the Republic of France, and residing in Paris, France, and CHARLES LIONEL MARCUS, citizen of the United States, and resident of the city of New York, in the county of New York and State of New York, have invented a new, original, and ornamental Design for Combined Stand and Holder for Perfume Bottles, of which the following is a specification, reference being had to the accompanying drawing, forming part thereof, in which—

Fig. 1 is a top plan view of a combined stand and holder for perfume bottle embodying our new design; and

Fig. 2 is a side view thereof.

We claim:

The ornamental design for a combined stand and holder for perfume bottles, as shown.

Signed at Paris, November 10, 1924.

BLANCHE STEVENS-ARVOY, née RENEAUX.

Signed at New York city, October 28, 1924.

CHARLES LIONEL MARCUS.
